UNITED STATES PATENT OFFICE.

DANIEL ROBERT CAMERON, OF VANCOUVER, BRITISH COLUMBIA, CANADA.

CATTLE GUARD.

Application filed February 2, 1924. Serial No. 690,204.

To all whom it may concern:

Be it known that I, DANIEL ROBERT CAMERON, a subject of the King of Great Britain, and a resident of the city of Vancouver, in the Province of British Columbia, Canada, have invented certain new and useful Improvements in Cattle Guards, of which the following is a specification.

My invention relates to improvements in cattle guards, and the object of my invention is to devise a simply constructed and maintained guard of great cheapness and durability which is of the highest efficiency in keeping cattle off railway tracks so that their loss through killing by trains is prevented.

I attain this object by the construction illustrated in the accompanying drawings in which—

20 Fig. 1 is a plan view of a middle section of the guard, in perspective.

Fig. 2 is a cross sectional view of the movable platform element.

25 Fig. 3 is a bottom plan view of a platform.

Fig. 4 is a view in side elevation illustrating the operation of the movable platform.

30 Fig. 5 is a plan view of the complete guard, in place.

Similar numerals of reference indicate similar parts throughout the several views.

The cattle guard arrangement herein described consists of two sets of complete guards, as shown in Fig. 5, one set, comprising the three sections 1, 2 and 3, being placed across the track 4 on one side of the crossing 5 and the other set, comprising the three sections 6, 7, and 8 being placed on the opposite side of the crossing. The side sections 1-3 and 6-8 are disposed outside the rails and between them and the respective embankments 9 and 10, while the middle sections 2-7 are placed between the rails, and as all the sections are of the same construction one middle section only, 2 in Fig. 5 and illustrated more particularly in Fig. 1, will be described, its detailed description, however, applying with equal force to the remaining sections.

55 The middle section 2, then, consists of a plurality of stationary platforms 11 and a tilttable one 12, the tilttable platform being arranged nearest the crossing and the stationary ones spaced therefrom. Each platform is, for the sake of cheapness, pref-

erably formed out of a number of pieces of wood 13 of a suitable kind and size connected together by longitudinal slats 14 and 15, as shown in Fig. 2, and the solid wood base thus constructed is covered on the upper side and round the edges with polished sheet metal, as indicated by the numeral 16 in Figs. 2 and 3, so that all the platforms, both the tilttable one and the stationary ones, 60 are characterized by great slipperiness. The stationary platforms 11 are secured to the edges of the railway ties 17 at a steep inclination and parallel to one another, the ties being bevelled as at 18 to permit the 65 platforms to be secured solidly thereto, and each platform extends at its lower edge close to the track bed 19 while at its upper edge it extends to within a short distance from the level of the top of the rails. The 70 width of each platform is such that when in place the upper edge of one platform overlaps the lower edge of the one next to it. The tilttable platform 12 is provided at each 75 end with eyes 20 and 21 so that it may be 80 connected freely to its respective tie by spikes 22, or other suitable means, driven through the eyes into the tie, and at the edge nearest the crossing it is provided with a counterweight 23 formed by raising the 85 metal covering into a form substantially triangular in cross section as at 24 and filling the space within the raised part with cement, as indicated by the numeral 25, the weight of which is sufficient to return the 90 platform to a normal horizontal position from a tilted one when freed from any weight thereon tilting it. The dimensions of the counterweight are such that when tilted it does not project above the level of 95 the top of the rails. The edge of the tilttable platform nearest the crossing and the upper edges of the two adjacent stationary ones are provided with a plurality of spikes 26, as shown in Figs. 1 and 4.

100 The manner in which the device operates and its utility will be readily apparent, on reference being had to the drawings and particularly to Fig. 4, as already stated the complete guard is placed across the track 105 on opposite sides of the crossing so that the entrance to the track on either side is guarded by first the normally horizontal tilttable platforms and then the normally inclined stationary ones. Thus, a cow approaching 110 the track to enter it steps with one foot on the horizontal platform 12 which im-

mediately tilts so that the foot of the animal slides downwardly on the slippery platform surface and in striving to recover footing the advanced leg contacts with the spikes of the inclined platform 11 while the leg outside the tilted platform contacts with the spikes on its upper edge so that the combined effect of the tilting platform and the spikes turns the animal away and balks its endeavours to cross the guard. Should it succeed in passing the tilttable one and step on the next inclined one the same effect is produced as the feet slide down the polished inclined surface while the spikes prick its legs so that its efforts are then directed towards returning to the crossing whence it came.

It will be seen therefore that I have de-

vised a simple, inexpensive, and efficient cattle guard capable of being used to great advantage for the protection of cattle against the dangers of straying on railway tracks.

What I claim as my invention is:

A cattle guard comprising a plurality of spaced inclined stationary platforms adapted to extend across a railway track and a normally horizontal tilttable platform in front of the stationary ones, the inclined platforms and the horizontal one when tilted extending at their lower edges to the track bed and at their upper edges not extending above the rail level.

Dated at Vancouver, B. C. this 9th day of January, 1924.

DANIEL ROBERT CAMERON.
